UNITED STATES PATENT OFFICE.

THOMAS J. GRAY, OF CHICAGO, ILLINOIS.

FLUID-MOTOR.

1,065,604.

Specification of Letters Patent. Patented June 24, 1913.

Application filed August 24, 1904, Serial No. 221,945. Renewed November 29, 1912. Serial No. 734,196.

To all whom it may concern:

Be it known that I, THOMAS J. GRAY, a citizen of the United States of America, and resident of Chicago, Cook county, Illinois, 5 have invented a certain new and useful Improvement in Fluid-Motors, of which the following is a specification.

My invention relates to fluid motors in general, and more particularly to gasolene, 10 gas or other internal combustion engines, and especially to engines or motors having a plurality of pistons.

Generally stated, the object of my invention is to provide an improved and highly 15 efficient fluid motor; and a special object is to provide an improved construction and arrangement for simplifying and improving the transmission of power from the pistons to the rotary shaft; and another object is to 20 provide an improved construction or arrangement for securing both a mechanically and explosively balanced engine or motor; and it is also an object to provide an improved construction and arrangement of 25 such character as to insure a powerful, smooth and even running of the engine.

To the foregoing and other useful ends my invention consists in matters hereinafter set forth and claimed.

30 In the accompanying drawings Figure 1 is a top plan view of an internal combustion engine involving the principles of my invention. Fig. 2 is a side view of the engine shown in Fig. 1. Fig. 3 is a horizontal section on line 3—3 in Fig. 2. Fig. 4 is a vertical section on line 4—4 in Fig. 1. Fig. 5 is an end view of the engine shown in Fig. 1, one-half of the engine being shown in cross section, and said section being taken on line 35 5—5 in Fig. 1. Fig. 6 is an enlarged detail of a portion of the valve actuating mechanism. Fig. 7 is an enlarged detail of one of the plates employed for connecting the pistons with the rotary shaft.

45 As thus illustrated, the casing of the engine is practically composed of three sections A, B, and C, the middle section A constituting a housing for the cams D and E, and the outer parallel sections B and C providing cylinders for the reciprocating pistons F, G and H, I, the same being arranged in pairs at opposite sides of said cams. The pistons F and G reciprocate toward and away from each other in the casing-section 50 B, the explosion chamber being located between them. In a similar manner, the pis-

tons H and I reciprocate toward and away from each other in the casing-section C, and the explosions occur between them. The cam D is provided with a zigzag or back and forth cam groove *d*, while the cam E is provided with a similar groove *e*. It will be seen that the two cam-grooves, although identical in principle, are of opposite formation. The two cams thus provided are 65 mounted upon a shaft J, the latter being in turn supported in bearings provided by the cylinder heads K, which latter are bolted to the ends of the middle casing-section.

It will be understood that the three sections of the casing can be secured together in any suitable or desired manner. Preferably, the outer casing-sections are provided in their opposing sides with slots *b*, *b*¹, *c*, *c*¹. Narrow spaces or ways L and M are provided between the middle casing-section and the two outer casing-sections. Four plates N, N¹, N², N³ are adapted to slide or reciprocate in these narrow spaces, and in unison with the pistons. In other words, 75 these plates constitute the means whereby power is communicated from the pistons to the said cams; and to such end each plate is provided with a roller or projection adapted to engage the groove in one of the 80 cams, and also with a pin or other projection adapted to engage one of the pistons and slide in one of the slots formed in the inner sides of the two cylinders. For example, the plate N² has a roller *n* adapted 90 to engage the cam-groove *d*, and is also provided with a pin or projection *n*¹ adapted to engage a transverse opening in the piston H; and it will be seen that this pin or projection *n*¹ reciprocates in the slot *c*. The 95 other plates are, it will be observed, the same as the plate shown in Fig. 7, which serves to connect its allotted piston with one of the cams. With this arrangement, it is obvious that fluid pressure applied between the pistons will cause the rollers on the plates N, 100 N¹, N² and N³ to act on the cam grooves—that is to say, first on one bevel and then on the next,—as to rotate the shaft J in its bearings. In other words, the pistons first 105 draw apart and thereby communicate motion to the shaft, and the momentum of the fly-wheel on the latter then causes the cams to bring the pistons together. In this way, the cams alternately communicate motion 110 from the pistons to the shaft and from the shaft to the pistons. As the pistons and

shaft are parallel with each other, and with the provision of the rotary cams, a very compact and powerful engine is obtained. The engine is perfectly balanced, it will be seen, both explosively and mechanically.

If the motor is to be employed as an internal combustion engine, it will be readily understood that the igniting, the admission and exhaust, and the mixing of the air and vapor, can be accomplished in any suitable, known or desired manner. As a matter of further improvement however, and as a valve mechanism which is particularly applicable to an engine of this character, each cylinder or outer section of the casing can be provided with admission and exhaust openings 1 and 2, as shown in Fig. 4, for example—controlled by admission and exhaust valves, 3 and 4. The space 5, between the two valves, may serve as a mixing chamber and communicates with the space or explosion chamber between the two pistons. The two valves can, of course, be of any suitable or desired form; but the exhaust valve 4 is preferably connected with the horizontal rod 6 and held normally closed by a spring 7; the rod 6 is mounted to reciprocate in bearing 8, and is held in this normal position by a spring 9. Said rod is also provided with a roller 10, as shown more clearly in Fig. 6. Between the two cams on the shaft J, a cam 11 is mounted and adapted to engage a reciprocating pin or finger 12. The upper end of this pin 12 is provided with a bevel 13 adapted to act on the roller 10 for the purpose of reciprocating the rod 6. With this arrangement, the rotation of the cam 11 effects, through the medium of the parts 12, 10 and 6, and the cross-piece 14, a proper reciprocation or opening and closing movement of the valve 4. It will be readily understood that the cam 11 must have any suitable formation or contour consistent with the manner in which the exhaust valve is to be operated. The same valve arrangement is, it will be seen, employed at the other side of the engine; and the cam 11 is, therefore, operative to open the two exhaust valves at the proper time. In the arrangement shown, the pistons move apart under the force of the explosions, then come together in order to effect the exhaust, then move apart again for the purpose of drawing in the motive fluid, and then come together again for the purpose of simultaneously compressing the two charges. It is evident, however, that there is an explosion, or, more properly speaking, two simultaneous explosions, to each complete rotation of the shaft. But any number of successive explosions may be employed to each rotation of the shaft without departing from the spirit of my invention. The ends of the spaces L and M serve as air pockets against which the outer

ends of the plates N, N¹, N² and N³ may cushion when the pistons move apart. A similar cushioning effect occurs between the opposing ends of said plates when the pistons come together.

Plates N, N¹, N², and N³ constitute slides which are actuated by the pistons, and which are mounted between the pistons and the cams. The rollers on these slides reciprocate back and forth in the slots a provided in the sides of the middle casing section A. With the arrangement shown, the shaft J is balanced against both lateral and endwise thrust. In other words, the lateral thrust of one piston on the shaft is counterbalanced by the lateral thrust of the piston on the other side of the shaft. In a similar way, the endwise thrust of the piston on the shaft is counterbalanced by the other piston on the same side of the shaft. Preferably, however, the endwise thrust of a pair of pistons mounted at opposite sides of the shaft is counteracted by the opposite endwise thrust upon the shaft by another pair of pistons also mounted on opposite sides of the shaft. In this way, the shaft is, as stated, practically free from both lateral and endwise thrusts in its bearings. Consequently, the engine as a whole is, as previously stated, balanced both explosively and mechanically.

Obviously, the explosions may occur alternately at opposite sides of the shaft, by suitably adjusting the valves and igniting means. The contact of the pistons at one side of the cams is offset or counteracted, as far as lateral thrust of the shaft is concerned, by the contact of the pistons at the other side. Probably simultaneous explosions at opposite sides of the shaft are calculated to effect a more perfect balancing.

What I claim as my invention is:

1. A fluid motor comprising a cylinder, a reciprocating trunk piston therein, a rotary shaft parallel with said piston, a rotary cam on said shaft, said cam being positioned at one side of said piston and having a zigzag and endless cam-groove, a slide mounted directly between the adjacent sides of the piston and cam, together with means carried by the slide for engaging said cam-groove and for engaging the side of the piston, whereby the reciprocation of said piston is converted into rotation on the part of the said shaft.

2. An internal combustion engine comprising a cylinder, a rotary shaft, another cylinder, a pair of pistons disposed at one side of said shaft, in one cylinder, a pair of pistons disposed at the opposite side of said shaft, in the other cylinder, the members of each pair of pistons having an explosion chamber between their opposing ends, a pair of zigzag and endless cam-grooves carried by said shaft, and means carried on the circumference or periphery of the said pistons

for engaging said cam-grooves, said shaft being thereby balanced against endwise thrust.

3. An internal combustion engine comprising a rotary shaft, a pair of pistons at each side of said shaft, a casing made in three parallel sections, the middle casing section inclosing said shaft, and the other casing sections each inclosing a pair of pistons, a pair of zigzag and endless cam-grooves carried by said shaft, reciprocating slides moving in spaces between the casing sections, and projections on said slides engaging said pistons and grooves.

4. An internal combustion engine comprising a casing, a rotary shaft supported in said casing, a pair of pistons working in the casing at one side of said shaft, a pair of pistons working in the casing at the other side of said shaft, the members of each pair of pistons having an explosion chamber between their opposing ends, a pair of zigzag and endless cam-grooves carried by said shaft, means actuated by said pistons and adapted to engage said cam-grooves, admission and exhaust valves, a pair of parallel horizontally arranged reciprocating rods connected with the exhaust valves, reciprocating members having beveled ends adapted to engage suitable portions of said rods, and a cam on said shaft for engaging said members and thereby operating said exhaust valves, the shaft and pistons being parallel.

5. The combination of a reciprocating piston, a rotatable member, and means for balancing said member against endwise thrust, and for converting the reciprocation of said piston into rotation on the part of said rotatable member, said means including rotary cams on said member, another piston, the two pistons opposing each other, and means carried on the circumference or periphery of the two pistons for engaging said cams, together with an explosion chamber between the opposing ends of said pistons.

6. An engine comprising a rotary shaft, a middle casing section in which said shaft is mounted, a cylinder secured to each side of said casing section, a pair of opposed pistons in each cylinder, said pistons and shaft being parallel, a pair of oppositely-formed cam-grooves carried by said shaft, slides mounted between the pistons and the shaft, and means on said slides for removably engaging said pistons, and for engaging said cam-grooves.

7. In an engine, the combination of a single continuous rotary shaft, a plurality of cylinders arranged in parallel relation to said shaft, a pair of trunk pistons in each cylinder, there being an explosion chamber between the members of each pair of pistons, and means for imparting rotary motion to the shaft from the sides or peripheries of

the pistons, said shaft being thereby balanced against endwise thrust.

8. In an engine, the combination of a central shaft balanced with respect to endwise thrust, a plurality of cylinders disposed on diametrically opposite sides of said shaft in axial parallel relation thereto, a pair of trunk pistons in each cylinder, there being an explosion chamber between the members of each pair of pistons, and means operatively related to the sides or peripheries of said pistons for imparting rotary motion to said shaft.

9. In an engine, the combination of two sets of axially-aligning trunk pistons, each piston of the same diameter as the one opposing it, cylinders for said pistons, there being an explosion chamber between the members of each pair of pistons, a single continuous rotary shaft mounted between said sets of pistons and in parallel relation thereto, and in a common plane therewith, and means disposed on said shaft and connected with the peripheries of said pistons, at points between the ends thereof, for converting the rectilinear reciprocating motion of said pistons into rotary motion of said shaft, said shaft being thereby balanced against endwise thrust.

10. In an engine, the combination of a single continuous rotary shaft balanced with respect to endwise thrust, a plurality of cylinders arranged in parallel relation to said shaft, a pair of balanced trunk pistons in each cylinder, said pistons each being of the same diameter as the one opposing it, there being an explosion chamber between the members of each pair of pistons, and means for imparting rotary motion to the balanced shaft from the circumference or periphery of said pistons without disturbing the balance thereof.

11. In an engine, the combination of a central shaft balanced with respect to endwise thrust, a plurality of cylinders disposed on diametrically opposite sides of said shaft in axial parallel relation thereto, a pair of trunk pistons in each cylinder, there being an explosion chamber between the members of each pair of pistons, and means operatively related to the circumference or periphery of said pistons for imparting rotary motion to said shaft.

12. In an engine, the combination of two sets of axially-aligning pistons, a single continuous rotary shaft mounted between said sets of pistons and in parallel relation thereto, and in a common plane therewith, and means on said shaft for converting the rectilinear reciprocating motion of said pistons into rotary motion of said shaft, by engaging the peripheries of said pistons, at points between the ends thereof, said shaft being thereby balanced against endwise thrust, cylinders for said pistons, there being an ex-

losion chamber between the members of each pair of pistons.

13. In an engine, the combination of a rotary shaft, a plurality of cylinders arranged in parallel relation to said shaft, a pair of trunk pistons in each cylinder, and means for imparting rotary motion to the shaft directly from the peripheries of the pistons, said means including cam-means fixed to said shaft and balanced, or practically balanced, with respect to the axial or end thrust communicated to the shaft from said pistons, there being an explosion chamber between the members of each pair of pistons, and the pistons at one side of the shaft being adapted to move in unison with the corresponding pistons at the other side thereof.

14. In an engine, the combination of a central shaft, a plurality of cylinders disposed on diametrically opposite sides of said shaft in axial parallel relation thereto, a pair of trunk pistons in each cylinder, there being an explosion chamber between the members of each pair of pistons, and means operatively related to the peripheries of said pistons for imparting rotary motion to said shaft, said means including cam-means fixed to said shaft and balanced, or practically balanced, with respect to the axial or end thrust communicated to the shaft from said pistons, and the pistons at one side of the shaft being adapted to move in unison with the corresponding pistons at the other side thereof.

15. In an engine, the combination of two sets of axially-aligning trunk pistons, a rotary shaft between said pistons in parallel relation thereto, and in a common plane therewith, cylinders inclosing said pistons, and means on said shaft for converting the rectilinear reciprocating motion of said pistons into rotary motion of said shaft, by engaging the peripheries of said pistons, at points between the ends thereof, said means including cam-means fixed to said shaft and balanced, or practically balanced, with respect to the axial or end thrust communicated to the shaft from said pistons, there being an explosion chamber between the members of each pair of pistons, and the pistons at one side of the shaft being adapted to move in unison with the corresponding pistons at the other side thereof.

16. An internal combustion engine comprising a cylinder, a rotary shaft, another cylinder, a pair of pistons disposed at one side of said shaft, in one cylinder, a pair of pistons disposed at the opposite side of said shaft, in the other cylinder, the members of each pair of pistons having an explosion chamber between their opposing ends, a pair of zigzag and endless cam-grooves carried by said shaft, and means actuated by the said pistons for engaging said cam-grooves, together with a cam mounted be-

tween the said cam-grooves, and exhaust valves operated by said cam.

17. An internal combustion engine comprising a cylinder, a rotary shaft, another cylinder, a pair of pistons disposed at one side of said shaft, in one cylinder, a pair of pistons disposed at the opposite side of said shaft, in the other cylinder, the members of each pair of pistons being of the same diameter and having an explosion chamber between their ends, a pair of zigzag and endless cam-grooves carried by said shaft, and means actuated by and carried on the circumference or periphery of the said pistons for engaging said cam-grooves, the pistons at one side of the shaft being adapted to move in unison with the pistons at the other side thereof, said shaft being thereby balanced against endwise thrust.

18. In an engine, the combination of two sets of axially-aligning trunk pistons, a rotary shaft between said sets of pistons, in parallel relation thereto, and in a common plane therewith, and means on said shaft for converting the rectilinear reciprocating motion of said pistons into rotary motion of said shaft, said means including cams fixed to said shaft and disposed directly between the two sets of pistons, and means carried by the inner sides of the pistons for engaging the cams, together with cylinders provided with slots for the connections between the pistons and cams.

19. In an engine, the combination of a rotary shaft, a plurality of cylinders arranged in parallel relation to said shaft, a pair of trunk pistons in each cylinder, and means for imparting rotary motion to the shaft from the pistons, said means including cams fixed to said shaft and disposed directly between the cylinders, and inclosed slides actuated by and carried at the inner sides of the pistons, for engaging the cams.

20. In an engine, the combination of a central shaft, a plurality of cylinders disposed on diametrically opposite sides of said shaft, in axial parallel relation thereto, a pair of trunk pistons in each cylinder, and means operatively related to said pistons for imparting rotary motion to said shaft, said means including cams fixed to said shaft and arranged between the cylinders, and inclosed slides actuated by and carried at the inner sides of the pistons, for engaging the cams.

21. An engine comprising a cylinder, a rotary shaft, another cylinder, cam grooves carried by the shaft, pistons parallel with and arranged at opposite sides of said shaft, in said cylinders, means carried by the periphery of one piston for engaging one of said grooves, and means carried by the periphery of another piston for engaging the other groove, said pistons being adapted to move simultaneously in opposite directions,

whereby the shaft is balanced against end-wise thrust.

22. In an engine, the combination of a rotary shaft, a cam secured to said shaft, a trunk piston parallel with said shaft, a slide disposed between the side of the piston and the side of the cam, means on one side of the slide for removably engaging the side of the piston, and means carried by the other side of the slide for engaging said cam, whereby the reciprocation of the piston is converted into a rotary motion on the part of said shaft.

23. In an engine, the combination of a cylinder, a rotary shaft, another cylinder, a couple of balanced cams secured to said shaft, a plurality of pairs of trunk pistons arranged parallel with said shaft, in said cylinders, slides intermediate of the pistons and cams, means for removably connecting the slides with the sides of the pistons, and means carried by the slides for engaging said cams, whereby the reciprocation of the pistons is converted into a rotary motion on the part of said shaft.

24. In an engine, the combination of a cylinder, a rotary shaft, a couple of cam-grooves carried by said shaft, a pair of

trunk pistons parallel with said shaft, in said cylinder, a couple of slides intermediate of the pistons and shaft, means for removably connecting the slides with the sides of the pistons, and means carried by the slides for engaging said cam-grooves, together with an explosion chamber between the opposing ends of said pistons, whereby the reciprocation of the pistons is converted into a rotary motion on the part of said shaft.

25. In an engine, the combination of a cylinder, a shaft, a zigzag and endless cam-groove carried by said shaft, a couple of trunk pistons arranged parallel with each other and with the shaft, in said cylinder, slides interposed between the pistons and the shaft, means for removably connecting the sides of the pistons with the slides, and means carried by the slides for engaging said cam-groove, whereby reciprocation of the pistons is converted into rotation of the shaft.

Signed by me at Chicago, Ills., this 19th day of August, 1904.
